KNITTED FABRIC

Filed Nov. 10, 1930

INVENTOR.

MORRIS B. GOLDBERG.

BY *Leonard L. Kalish*
ATTORNEY.

UNITED STATES PATENT OFFICE

MORRIS B. GOLDBERG, OF PHILADELPHIA, PENNSYLVANIA, ASSIGNOR TO EAGLE KNITTING MILLS, INC., OF PHILADELPHIA, PENNSYLVANIA, A CORPORATION OF DELAWARE

KNITTED FABRIC

Application filed November 10, 1930. Serial No. 494,524.

My invention relates to knitted fabrics especially adapted for use as garment cloths for women's suits and dresses, particularly sport suits and the like.

5 The object of my present invention is to provide a knitted fabric having suitable body or thickness without excessive weight, and in which the transverse resiliency, elasticity or "stretch" which is so pronounced in 10 common knitted fabrics, is entirely eliminated, without however, detracting from the other desirable characteristics of the knitted cloth.

With the above and other objects in view, 15 which will appear more fully from the following detailed description, my invention consists of a knitted cloth or fabric comprising a knitted structure formed of knitted loops of a soft and bulky crinkled, artificial 20 or synthetic cellulose thread or the like, extending continuously across the fabric and certain crinkled artificial cellulose thread extending transversely through the fabric in a straight formation without being looped 25 or knitted but merely disposed within the fabric weft-wise, whereby a bulky and yet light knitted body is formed having no transverse elasticity, resiliency or "stretch" and having but a minimum longitudinal 30 elasticity, resiliency or "stretch," and having other desirable characteristics of texture tending towards extreme durability and wear, and adapting said fabric more particularly for garment cloths.

35 For the purpose of illustrating my invention, I have shown in the accompanying drawings, a form thereof which is at present preferred by me, since the same has been 40 found in practice to give satisfactory and reliable results, although it is to be understood that the various instrumentalities of which my invention consists can be variously arranged and organized and that my 45 invention is not limited to the precise arrangement and organization of the instrumentalities as herein shown and described.

Referring to the drawings in which like reference characters indicate like parts:

50 Figure 1 represents a plan view of a frag-

mentary portion of my novel knitted fabric, shown somewhat enlarged and diagrammatically.

Figure 2 represents a fragmentary and much enlarged diagrammatic view of the 55 composite thread of which my novel knitted fabric is formed.

Figure 3 represents an end view of my 60 novel knitted fabric shown on a much enlarged scale, merely to illustrate the manner in which the knitted and non-knitted threads are related to each other in the fabric.

In carrying out my invention, I may utilize any double bed straight (or circular) 65 knitting machine, with the two needle beds disposed at a suitable angle to each other, and having a suitable carriage adapted to traverse the needle beds, and to carry across said needle beds a suitable yarn carrier with 70 a thread for knitting the looped body of the fabric by continuous-thread and inter-looped rows of stitches or loops formed alternately on the two opposed and coacting banks or 75 rows of needles in the two needle beds.

Upon one of the carriage and carrier guide bars of the machine, I mount a special weft 80 yarn carrier, (which apparatus does not form the subject matter of the present application) for laying a weft-like or filler 85 thread; said weft carrier being provided with a certain novel carrier box and having a certain novel stopper related thereto, which so coact with the corresponding spring pressed plunger of the carriage as to cause said weft 90 carrier to lead the first mentioned knit-yarn carrier by a suitable number of needles, so that the weft thread will be laid into the fabric (but not into the needles of either row), and so that the weft thread laid by this weft carrier will be disposed in the center of the fabric and will be encased between the opposed sets of knitted loops forming the two opposed faces of the fabric.

I may employ, for both the knit-strand 4 95 as well as for the weft-strand 5, a certain composite form of a soft and bulky or crinkled artificial or synthetic cellulose thread illustrated, much enlarged and somewhat diagrammatically, in Figure 2. This 100

composite thread illustrated particularly in Figure 2 consists of a taut center or core filament or strand 6, which may be of artificial cellulose, and around which an outer strand 5 or filament 7, preferably of artificial cellulose, is loosely wrapped or twisted in a generally spiral formation;—with certain enlargements of loops formed at suitable intervals, which create slight enlargements or nubs 8 along the thread at the suitable intervals, which may be a sixteenth to an eighth of an inch apart.

The effect of this composite thread construction, is a loose twisted soft and somewhat bulky thread, having no substantial longitudinal elasticity or "stretch", but having nevertheless, a soft, loose and bulky body, and a crinkled or roughened exterior with slight nubs at intervals.

My novel knitted fabric illustrated in Figures 1 and 3 of the drawing, is formed by knitting one strand of this composite crinkled thread into a two-faced fabric, that is, a fabric having ribs on both faces thereof, and laying another strand of this composite crinkled thread into the fabric, with each course of knitted looped stitches on each side of the fabric, so that said second or weft strand will be disposed within said fabric in a substantially straight and un-looped formation, in a weft-like manner, producing an appearance somewhat like that shown in Figure 1.

The resultant fabric will be substantially non-elastic and free of "stretch" transversely, because of the taut core filament or strand 6 of the composite weft strand 5, and will possess but a minimum of elasticity or "stretch" longitudinally, because of a certain interlocking and filling effect produced by the soft and bulky or loose crinkled threads in the loop formation and weft formation.

The resultant fabric will however, possess certain other characteristics of knitted fabrics to an increased degree, to wit, lightness and softness combined with a bulkiness of body, and will possess in addition to such qualities normally inherent in knitted fabrics, and added quality of firmness not present in knitted cloths, as well as the ability to retain its shape or "set", which quality is likewise not possessed by common knitted cloths.

I am aware that my invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention, what I hereby claim as new and desire to secure by Letters Patent, is:—

1. A knitted fabric comprising opposed rows of interlooped knitted loops of a loosely twisted thread having a relatively taut core strand, and an un-knitted loosely twisted thread, having a relatively taut core, extending through the fabric in a substantially straight formation intermediate of the opposed rows of interlooped knitted loops and encased therebetween;—said fabric being relatively non-stretching transversely. 75

2. A knitted fabric comprising opposed rows of interlooped knitted loops of a loosely twisted and relatively bulky thread including synthetic cellulose having a relatively taut core strand, and an un-knitted loosely twisted and relatively bulky thread including synthetic cellulose, having a relatively taut core, extending through the fabric in a substantially straight formation intermediate of the opposed rows of interlooped knitted loops and encased therebetween;—said fabric being relatively non-stretching transversely. 80

3. A knitted fabric comprising opposed rows of interlooped knitted loops of a loosely twisted crinkled thread, and an un-knitted loosely twisted crinkled thread extending through the fabric in a substantially straight formation intermediate of the opposed rows of interlooped knitted loops and encased therebetween;—said fabric being relatively non-stretching transversely. 90

4. A knitted fabric comprising opposed rows of interlooped knitted loops of a loosely twisted and relatively bulky and crinkled thread including synthetic cellulose, and an un-knitted loosely twisted and relatively bulky thread including synthetic cellulose, extending through the fabric in a substantially straight formation intermediate of the opposed rows of interlooped knitted loops and encased therebetween;—said fabric being relatively non-stretching transversely. 100

5. A knitted fabric comprising opposed rows of interlooped knitted loops of a loosely twisted and relatively bulky thread including synthetic cellulose, and an un-knitted loosely twisted and relatively bulky thread including synthetic cellulose, having a relatively taut core, extending through the fabric in a substantially straight formation intermediate of the opposed rows of interlooped knitted loops and encased therebetween;—said fabric being relatively non-stretching transversely. 110

6. A knitted fabric comprising opposed rows of interlooped knitted loops of a loosely twisted and relatively bulky thread including synthetic cellulose, and an un-knitted loosely twisted and relatively bulky thread including synthetic cellulose, extending through the fabric in a substantially straight and taut formation intermediate of the opposed rows of interlooped knitted loops and encased therebetween;—said fabric being relatively non-stretching transversely. 120

7. A knitted sportwear fabric comprising 125

opposed rows of interlooped knitted loops of a
relatively loosely twisted and relatively bulky
crinkled thread including synthetic cellulose
and an unknitted thread extending through
5 the fabric in a generally straight and taut
formation intermediate the opposed rows of
interlooped knitted loops, and encased there-
between, said fabric being relatively non-
stretching transversely.

10 In testimony whereof I have hereunto set
my hand this 5th day of November, 1930.

MORRIS B. GOLDBERG.
